COVER FOR GARMENT HANGERS

John W. Johnson, St. Maries, Idaho

Application January 3, 1938, Serial No. 183,111

6 Claims. (Cl. 223—98)

My present invention relates to improvements in covers for garment hangers and more particularly to covers for the conventional hangers adapted to support coats and dresses or other apparel having shoulder straps or wide, low-cut neck lines.

At the present time, the garment hangers in general use comprise a length of wire bent into substantially triangular shape, and having a hook 10 formed adjacent the apex of the triangle. The wire is usually painted or otherwise coated to prevent rust and to enhance the appearance of the hanger, and such painting or covering tends to give the hanger a smooth slippery surface. 15 Garments hung on the smooth surfaced hangers, as by shoulder straps, are apt to slip off and fall to the floor with the consequent soiling and mussing of the garment.

The principal purpose of my invention then, is to provide these garment hangers with a surface 20 covering which will retain the garment, or the shoulder straps, in adjusted position, without the use of expensive mechanical means, and without altering or changing the original hanger.

25 In the accompanying drawing I have illustrated one complete example of the physical embodiment of my invention according to the best mode I have thus far devised, but it will be understood that changes and alterations may be made in the exemplified structure within the scope of the appended claims.

In the drawing Figure 1 is a perspective view of the garment hanger cover.

Figure 2 is a front elevation of the cover secured in position on a hanger.

35 Figure 3 is a transverse sectional view of the cover.

Figure 4 illustrates a modified form of my cover.

40 Figure 5 is a perspective view of a portion of another modified cover.

Figure 6 is a sectional view of the cover and hanger taken along line 6—6 of Figure 2.

Referring now to the drawing, 1 represents the 45 cover of my invention of substantially rectangular shape and which, preferably, consists of a strip of sponge rubber, and is of lesser length than the hanger on which it is to be used. Other suitable materials such as crepe paper or other rough surfaced materials may be employed to advantage however. The cover 1 is provided with an eyelet 2 centrally disposed thereof. The ends 3 and 4 of the cover are folded as at 5 and 6, and the folded portions are attached together as by 50 means of staples 7 and 8 to form pockets. The 55

ends may also be secured if desired by cementing or by other suitable manner.

In use the cover 1 is employed in conjunction with the conventional garment hanger as 9 having the angular supporting arms 10 and 11 forming corners or bends 12 and 13, and having the bracing arm 14. The upper ends of the arms 10 and 11 are twisted together as at 15, and one end continues upward to form the hook 16.

In securing the cover 1 on the hanger 9, the 10 eyelet 2 of the cover is passed over the hook 16 until the under side of the eyelet rests on the adjacent portions of the arms 10 and 11. The ends 3 and 4 of the cover are then stretched to the desired length and the pockets formed by the 15 folds 5 and 6 are placed over the covers 12 and 13 of the hanger.

Thus the cover is detachably secured in position and is not susceptible to being dislodged accidentally.

20 The sponge rubber cover strip being of a rough texture will not permit the shoulder straps, or the shoulders of the garments hung thereon, to slip therefrom and the garments will be supported in the desired manner, by friction there- 25 between.

In the modification shown in Figure 4, I have provided the cover 1 with an elastic re-inforcing strip 17 secured by cementing or stapling on the under side of the cover adjacent the ends thereof, to prevent the penetration of the hanger corners, although these strips are not necessary unless the hanger corners are bent in a sharp angle.

30 In Figure 5 I have illustrated a modified manner in which the ends of the cover 1 are folded 35 transversely upon themselves as at 18, and the folded portions are secured to the body of the cover as by staples 19 and 20. The staples are spaced from each other in order that the corner of the hanger may be inserted between the folded 40 portion 18 and the cover 1, and the cover is attached or mounted on the hanger in the same manner as set forth in relation to Figure 2.

Having thus fully described my invention what I claim as new and desire to secure by Letters 45 Patent is:

1. A cover for garment hangers comprising an elastic strip having a rough surface and having a central opening therethrough, the ends of said strip being folded, and the adjoining faces of the 50 folded portions secured together to form pockets adapted to receive the corners of said hanger.

2. A cover for garment hangers comprising an elastic strip having a rough surface, the ends of said strip being folded longitudinally, and the ad- 55

- joining faces of the folded portions secured together to form pockets adapted to receive the corners of said hanger.
3. A cover for garment hangers comprising an elastic strip having a rough surface, the ends of said strip being folded transversely against the body and the adjoining faces of the folded portion and the body secured together to form pockets adapted to receive the corners of said hanger.
4. A cover for garment hangers comprising an elastic strip the ends of said strip being folded to form pockets adapted to receive the corners of said hanger, and the folded portion of said cover having an elastic re-inforcing strip forming a liner for said pockets.
5. An accessory for hangers comprising, a channel shaped member made of rubber and adapted to overlie the top of a hanger, and having end pockets formed therein adapted to receive the tips of the hanger.
6. An accessory for hangers comprising, a channel shaped member made of elastic material having a friction surface and having a length less than the length of the hanger, said member being formed to overlie the top edge of the hanger and having end pockets formed therein adapted to engage the tips of the hanger when stretched thereover.

JOHN W. JOHNSON.
